UNITED STATES PATENT OFFICE.

OMER M. GLUNT, OF RUTHERFORD, NEW JERSEY, ASSIGNOR TO WESTERN ELECTRIC COMPANY, OF NEW YORK, N. Y., A CORPORATION OF ILLINOIS.

SPRING-JACK.

1,126,193.

Specification of Letters Patent. Patented Jan. 26, 1915.

Application filed August 28, 1913. Serial No. 787,129.

To all whom it may concern:

Be it known that I, OMER M. GLUNT, a citizen of the United States, residing at Rutherford, in the county of Bergen and State of New Jersey, have invented a certain new and useful Improvement in Spring-Jacks, of which the following is a full, clear, concise, and exact description.

This invention relates to a type of electrical switch commonly known as a spring-jack, which jack is adapted to coöperate with a plug in order to detachably connect a plurality of electrical conductors associated with the plug with corresponding conductors associated with the jack. Jacks of this type are commonly employed in telephone switchboards in which a large number of jacks are mounted in close proximity, making it desirable that the jack structure be as compact as is consistent with the size of the ordinary switchboard plug, and be sufficiently rigid to prevent lateral displacement thereof and hence to maintain the contact springs and sleeve of the jack in alignment so that they will properly coöperate with the plug and will not interfere with adjacent jacks.

It is an object of this invention, therefore, to construct a spring-jack which will be rigid, compact and which may be conveniently attached to the ordinary switchboard.

With these objects in view a frame is provided, which frame carries both the jack sleeve and the contact springs. This frame is a box-like structure having two sides at right angles to each other and an endpiece attached to said sides at right angles thereto. The jack sleeve is mounted on the end portion of the frame and the contact springs are mounted on the side portion.

The invention will be more completely understood by referring to the accompanying drawings wherein—

Figure 1 is a side elevation of one form of spring-jack embodying the invention; Fig. 2 is a perspective view of the jack shown in Fig. 1; and Figs. 3 and 4 are perspective views of modified form of jack frames embodying the invention.

Referring first to the form of the invention shown in Figs. 1 and 2, the jack comprises a sleeve 1 which is secured at right angles to a sheet metal plate 2. The plate 2 is provided with a lug 3 having an aper-

ture therein by means of which the jack is adapted to be attached to the switchboard.

Secured to the plate 2, preferably by means of an electrically welded joint, is the jack frame 4. This frame 4 is punched from a single piece of sheet metal which is longitudinally bent along its center line to form two side portions 5 and 6, which side portions are at substantially right angles to each other. The side portion 6 is provided with a cut-away portion 7, thus forming a lug 8 which is welded to the plate 2 and the side portion 4, as is more clearly shown in Fig. 2, is provided with a downwardly offset portion 9 which is secured to the plate 3 preferably by welding. As more clearly shown in Fig. 2, the cut-away portion 7 is adjacent the lug 3 so that when an ordinary screw is passed through the aperture in the lug 3, the head of the screw will clear the jack frame, whereby the jack may be conveniently attached to and removed from the switchboard with the ordinary screw-driver. The downwardly offset portion 9 of the side portion 5 provides a clearance space for the end of the plug, and the opening 24 in such end portion 9 makes it impossible for the tip of the plug to contact with the jack frame.

Mounted on the side piece 5 of the angular frame 4 is a series of contact springs 10, 11 and 12. These contact springs are secured to the side piece 5 by means of screws 13 which pass through the rear ends of the contact springs, and through a plurality of strips of insulating material 14 which serve to insulate the contact springs from each other and from the jack frame. The screws 13 are insulated from the contact springs by sleeves of insulating material, not shown. It is obvious that the contact springs may be mounted on either of the side pieces 5 or 6, and that the jack may be mounted in the switchboard with either of the side portions disposed vertically, depending upon whether or not it is desirable to mount the contact springs in a vertical or a horizontal position.

Coöperating with the contact spring 12 is a contact piece 15 which is directly connected to the frame of the jack. The contact piece 12 also carries an insulating piece 16, which serves to insulate such spring from contact spring 11, and said contact piece 12 is also provided with a bent end 17 which is

adapted to coöperate with a plug when it is inserted in the jack.

In the modified form of the invention shown in Fig. 3, the sleeve passes through 5 the plate 2 and is riveted to the end 18 of the jack frame, thus serving to hold the jack frame and plate 2 together. The jack frame in this case is punched from a single piece of sheet metal, and in order to prevent 10 said frame from rotating relative to the plate 2, the plate 2 is formed with a projection 19, which projects into an aperture 20 of the jack frame. The projection 19 is preferably formed by punching out a lug on 15 the plate 2 and, by the same operation, forcing said lug into the aperture 20.

In the form of jack shown in Fig. 4, the jack frame 21 is punched from a single piece of sheet metal, the end 23 thereof being 20 provided with an integral metal lug 22, the plate 2 being omitted. The sleeve 1 of the jack is riveted directly to the end 23 of the jack frame. The contact springs are mounted upon jacks, in Figs. 3 and 4 in the 25 same manner as they are mounted upon the jack disclosed in Figs. 1 and 2.

In all of the various forms of jacks disclosed herein the jack frames are formed from a substantially rectangular sheet metal 30 blank, which blank is bent along its longitudinal center line providing two side portions at right angles to each other so that a cross-section of the frame is substantially L-shaped. Either secured to the end of the 35 side portions by welding or riveting, or integral therewith, is an end portion, which end portion is at right angles to both of the side portions.

By virtue of this construction, the frame 40 is made very rigid and the contact springs and sleeve of the jack which are carried by the frame are maintained in alignment.

The construction is compact, strong and

easy to assemble, and as the parts, with the exception of the sleeve, are all of sheet 45 metal, the jack can be cheaply manufactured in large quantities.

I claim:

1. In a spring jack, a punched frame comprising an end portion and two side portions disposed at right angles to each other and to said end portion and contact members carried by said end and side portions. 50

2. In a spring jack, a punched sheet metal frame comprising an end portion and two side portions disposed at right angles to each other and to said end portion, contact springs mounted upon one of said side portions, a sleeve member carried by said end portion and means carried by said frame for 55 securing the jack to a switchboard.

3. In a spring jack, a punched sheet metal frame comprising an end portion and two angularly disposed side portions, contact members carried by said end and side portions and an attaching lug punched out of 60 one of said side portions and extending at right angles thereto.

4. In a spring jack, a sheet metal frame comprising an end portion and angularly disposed side portions extending at right angles to said end portion, one of said side portions being provided with an opening adjacent the end portion, spring contact members mounted upon one of said side portions 70 with their ends adjacent said opening, and a mounting lug for said jack punched out of 75 one of said side portions.

In witness whereof, I hereunto subscribe my name this 23rd day of August A. D., 80 1913.

OMER M. GLUNT.
